(57) **ABSTRACT**

An object of the present application is to obtain a door-pinch detection device and an elevator door device that enable detection of a string-shaped object. Accordingly, the elevator door device of the present application includes: a door panel of an elevator; and a first attachment section and a second attachment section installed on at least either one of a front face or a back face of the door panel, the first attachment section including a pressure sensor, the second attachment section including a repulsive member installed in a manner for the pressure sensor to be housed therein when doors of the elevator are closed, thus enabling adjustment of an angle of the pressure sensor relative to the door panel. Therefore, door-pinch of an alien object can be detected with an improved accuracy.

DOOR-PINCH DETECTION DEVICE AND ELEVATOR DOOR DEVICE

CROSS-REFERENCE TO RELATED APPLICATION

The present application is based on PCT filing PCT/JP2018/039310, filed Oct. 23, 2018, the entire contents of which are incorporated herein by reference.

FIELD

The present invention relates to a door-pinch detection device and an elevator door device.

BACKGROUND

An elevator door device is equipped with a variety of sensors that detect an alien object likely to get pinched between doors when the doors are closed for the purpose of ensuring safety for boarding and alighting passengers. A thin elongated object and a string-shaped object to be attached to a pet such as a dog are relatively difficult for the sensors to detect due to the small diameters thereof.

As a method for solving such a problem, for example, a method as in PTL 1 has been known, where a pressure sensor is provided in a vertical direction on a door hitting face of one of doors while a cushioning member is provided at an end portion of the other door.

In PTL 1, the pressure sensor detects a pressure resulting from an elongated object or a string-shaped object, which intersects the door hitting face, being pressed via the cushioning member to detect an alien object.

In addition, for example, PTL 2 discloses a pressure-sensitive sensor for detecting a string-shaped object on a side face of one of doors. The pressure-sensitive sensor is fixed to a car door via a fixation hole made in a receiving member.

CITATION LIST

Patent Literature

[PTL 1] JP 2008-143619 A (see paragraph 0024, FIG. 2, etc.)
[PTL 2] JP 2007-131389 A (see paragraph 0015, FIG. 4, etc.)

SUMMARY

Technical Problem

Meanwhile, to reduce a door hitting sound caused immediately before door panels of an elevator are fully closed, the two door panels are often installed with door hitting faces thereof inclined in an inverted V-shape and thus the door hitting faces of the doors on both sides are unlikely to be parallel with each other. In a case where the pressure sensor and the cushioning member of PTL 1 are installed with the door hitting faces of the doors on both sides being not in parallel with each other, one of a lower side and an upper side of the pressure sensor is spaced from the cushioning member at a distance of several millimeters. If the lower side of the pressure sensor is spaced from the cushioning member, the door-pinch of an alien object cannot be detected at the lower side of the pressure sensor due to a failure of the pressure sensor and the cushioning member to contact with each other even when the doors are closed, although the

2

door-pinch of an alien object can be correctly detected at the upper side of the pressure sensor.

Accordingly, in installing the pressure sensor and the cushioning member in an existing elevator, it is necessary to reinstall the doors to adjust the angles of the doors, which makes the installation of the door-pinch detection device time-consuming.

Further, PTL 2, which discloses the receiving member having the fixation hole for attaching the pressure-sensitive sensor to the car door, is silent about adjusting the inclination of the pressure-sensitive sensor with respect to the inclination of the door of an elevator. Therefore, in a case where the door hitting faces are attached while being inclined in an inverted V-shape, the door-pinch of an alien object fails to be correctly detected.

An object of the present application is to obtain a door-pinch detection device and an elevator door device that solve the above-described problems and enable detection of a string-shaped object.

Solution to Problem

A door-pinch detection device of the present application includes: a first attachment section and a second attachment section attached to at least either side face of a front face or a back face of a door panel of an elevator, the first attachment section including a pressure sensor, the second attachment section including a repulsive member installed in a manner for the pressure sensor to be housed therein; and at least either one of a first angle adjustment section provided in the first attachment section to adjust an attachment angle of the pressure sensor with respect to the door panel for installation or a second angle adjustment section provided in the second attachment section to adjust an attachment angle of the repulsive member with respect to the door panel for installation.

Further, an elevator door device of the present application includes: a door panel of an elevator; a door-pinch detection device including a first attachment section and a second attachment section installed on at least either one of a front face or a back face of the door panel, the first attachment section including a pressure sensor, the second attachment section including a repulsive member installed in a manner for the pressure sensor to be housed therein when doors of the elevator are closed; and a third angle adjustment section provided in the door panel to adjust an attachment angle of at least either one of the first attachment section or the second attachment section for installation.

50 Advantageous Effects of Invention

The door-pinch detection device and the elevator door device according to the present application enable the adjustment of an angle of the pressure sensor relative to the door panel, thus enabling an improvement in accuracy in detecting the door-pinch of an alien object.

BRIEF DESCRIPTION OF DRAWINGS

60 FIG. 1 is block diagram of a door device including a door-pinch detection device of the present application.

FIG. 2a is a figure showing the inclination of a car-side door panel of a door-pinch detection device of Embodiment 1 of the present application.

65 FIG. 2b is a figure showing the inclination of the car-side door panel of the door-pinch detection device of Embodiment 1 of the present application in another case.

FIG. 3 is a perspective drawing of a door device including the door-pinch detection device of Embodiment 1 of the present application.

FIG. 4a is a sectional drawing of the door device including the door-pinch detection device of Embodiment 1 of the present application.

FIG. 4b is a sectional drawing of the door device including the door-pinch detection device of Embodiment 1 of the present application.

FIG. 5 is a perspective drawing of a door device including a door-pinch detection device of Embodiment 2 of the present application.

FIG. 6 is a sectional drawing of the door device including the door-pinch detection device of Embodiment 2 of the present application.

FIG. 7 is a perspective drawing of a door device including a door-pinch detection device of Embodiment 3 of the present application.

FIG. 8 is a sectional drawing of the door device including the door-pinch detection device of Embodiment 3 of the present application.

FIG. 9 is a control flowchart of the door device of the present application.

DESCRIPTION OF EMBODIMENTS

Embodiment 1

A door-pinch detection device 10 and a door device 100 for an elevator according to Embodiment 1 of the present application will be described below with reference to the drawings.

FIG. 1 shows a structure of the door device 100 for an elevator of Embodiment 1 of the present application. The door device 100 is a door device for an elevator car. The door device 100 includes the door-pinch detection device 10. The door-pinch detection device 10 includes a first attachment member 11 (first attachment section) and a second attachment member 12 (second attachment section). The first attachment member 11 is attached to a car-side door panel 21, while the second attachment member 12 is attached to a car-side door panel 22.

The car-side door panels 21 and 22 are coupled to a door device support frame 20 provided above. A coupler 23a, a coupler 23b, a rail 24, a door hanger 25a, a door hanger 25b, a hanging handle 26a, a hanging handle 26b, a belt 27, a lazy-side pulley 28, and a motor 29 are provided in the door device support frame 20.

The car-side door panels 21 and 22 are fixed to the coupler 23a and the coupler 23b, respectively. The coupler 23a and the coupler 23b move right and left in FIG. 1 along the rail 24, which is horizontally provided, via the door hanger 25a and the door hanger 25b.

The door hanger 25a and the door hanger 25b roll right and left on the rail 24. The hanging handle 26a is attached to the coupler 23a. The hanging handle 26b is attached to the coupler 23b. The hanging handle 26a is fixed to the coupler 23a at one end while being fixed to the belt 27 at the other end. The hanging handle 26b is fixed to the coupler 23b at one end while being fixed to the belt 27 at the other end. The belt 27 is an endless belt wound on the lazy-side pulley 28 and a pulley of the motor 29.

The lazy-side pulley 28 and the motor 29 are horizontally fixed to the door device support frame 20. The belt 27 rotates with the driving of the motor 29. The hanging handle 26a is fixed to the belt 27 on an upper side relative to the lazy-side pulley 28 and the pulley of the motor 29. The hanging handle

26b is fixed to the belt 27 on the lower side relative to the lazy-side pulley 28 and the pulley of the motor 29.

Thus, when the belt 27 rotates clockwise, the car-side door panel 21 moves right in FIG. 1 and the car-side door panel 22 moves left. Meanwhile, when the belt 27 rotates counterclockwise, the car-side door panel 21 moves left in FIG. 1 and the car-side door panel 22 moves right.

Such a structure causes a torque of the motor 29 to be transmitted to each of the car-side door panels 21 and 22. 10 Further, the open and close motion of the car-side door panels 21 and 22 is enabled by switching the rotation direction of the motor 29.

Meanwhile, dotted lines in FIG. 1 show hall-side door panels 31 and 32. The hall-side door panels 31 and 32 are 15 removably fixed to the car-side door panels 21 and 22 by a coupling device 33a and a coupling device 33b.

During the open and close motion of the car-side door panels 21 and 22, since the hall-side door panels 31 and 32 are fixed to the car-side door panels 21 and 22, the hall-side door panels 31 and 32 also perform an open and close motion with the open and close motion of the car-side door panels 21 and 22.

A pressure sensor 11a of the first attachment member 11 and the motor 29 are coupled to a door controller 40. When 25 a car arrives at each floor, the door controller 40 transmits a control instruction to the motor 29. The door controller 40 also transmits a control instruction to the motor 29 on the basis of an operation of an operating panel (not shown) in the car performed by a user.

Further, the first attachment member 11 transmits a detection result to the door controller 40. When it is detected that an alien object is pinched by the first attachment member 11 during the door close motion of the car-side door panels 21 and 22, the door controller 40 transmits a signal for stopping the door close motion or a signal for switching to the door open motion to the motor 29.

A detailed configuration of each of the first attachment member 11 and the second attachment member 12 will be described later.

It should be noted that the door controller 40 manages the open and close motion of the car-side door panels 21 and 22 while communicating with a control panel (not shown) that manages the motion of the whole of an elevator. The control panel controls the driving of a traction machine of the elevator on the basis of, for example, call registration and destination floor registration.

Here, the inclination of each of the car-side door panels 21 and 22 and the attachment angle of each of the first attachment member 11 and the second attachment member 12 will be described with reference to FIG. 2a.

To reduce a door hitting sound caused immediately before full close, the car-side door panel 21 is attached to the coupler 23a with a slight counterclockwise inclination.

Meanwhile, the car-side door panel 22 is attached to the coupler 23b with a slight clockwise inclination.

That is, the door hitting face 21a of the car-side door panel 21 and the door hitting face 22a of the car-side door panel 22 are in a V-shape.

Thus, even when a lower end of the door hitting face 21a and a lower end of the door hitting face 22a come into contact with each other during the door close motion, an upper end of the door hitting face 21a and an upper end of the car-side door panel 22 are spaced from each other by several millimeters.

65 Since the car-side door panels 21 and 22 are installed while being inclined in opposite directions to each other as described, the entire face of the door hitting face 21a and the

entire face of the door hitting face **22a** are prevented from simultaneously coming into contact with each other during the door close motion, thereby making it possible to reduce a contact sound caused by the door hitting faces **21a** and **22a**.

However, attaching the first attachment member **11** and the second attachment member **12** respectively to the car-side door panels **21** and **22** in parallel with the door hitting faces **21a** and **22a** entails a problem that the accuracy of the first attachment member **11** in detecting an alien object is different between upper portion and lower portion of each of the car-side door panels **21** and **22**.

Hence, it is necessary to attach the first attachment member **11** and the second attachment member **12** to the car-side door panels **21** and **22** at angles different from those of the door hitting faces **21a** and **22a**.

Accordingly, in the present application, the first attachment member **11** and the second attachment member **12** are attached while being angled with respect to the door hitting faces **21a** and **22a**. The first attachment member **11** and the second attachment member **12** are attached such that they are parallel with each other when doors of the elevator are closed.

It should be noted that the configuration where the door hitting face **21a** of the car-side door panel **21** and the door hitting face **22a** of the car-side door panel **22** are in a V-shape is described with reference to FIG. **2a**. However, the door hitting faces **21a** and **22a** are sometimes in an inverted V-shape when the doors are closed as shown in FIG. **2b** depending on the installation manner of the car-side door panels **21** and **22**. Even in such a case, the first attachment member **11** and the second attachment member **12** are attached with respect to the door hitting faces **21a** and **22a** such that the first attachment member **11** and the second attachment member **12** are in parallel with each other when the doors are closed.

Further, even in a case where the car-side door panels **21** and **22** are installed with the door hitting faces **21a** and **22a** being in parallel with each other, the car-side door panels **21** and **22** are sometimes inclined in a V-shape or an inverted V-shape as shown in FIG. **2a** or FIG. **2b** during the door close motion. Accordingly, with the inclination of each of the car-side door panels **21** and **22** during the door close motion taken into consideration in advance, the first attachment member **11** and the second attachment member **12** are attached while being inclined with respect to the door hitting faces **21a** and **22a**.

FIG. **3** is a perspective drawing of the car-side door panels **21** and **22**. FIG. **4a** is an A-A sectional drawing in FIG. **3** and FIG. **4b** is a B-B sectional drawing in FIG. **3**. FIG. **3** is a perspective drawing of the car-side door panels **21** and **22** with the door hitting faces **21a** and **22a** inclined in a V-shape as shown in FIG. **2a**. In FIG. **4a** and FIG. **4b**, an upper side in the figure is a car side and a lower side in the figure is a hall side. It should be noted that FIG. **3** shows an alien object, namely, string 1, between the car-side door panels **21** and **22**.

A detailed configuration of each of the first attachment member **11** and the second attachment member **12** will be described. The pressure sensor **11a** is provided at a distal end of the first attachment member **11**. An elongated hole **11b** (first angle adjustment section) and a pin hole **11c** are made in the first attachment member **11**. The first attachment member **11** is fixed to the car-side door panel **21** with a fitting **13**, such as a pin, a screw, or bolt and nut, penetrating each of the elongated hole **11b** and the pin hole **11c**. The

elongated holes **11b** and **12b** are each a hole elongated in the opening-closing direction of the doors.

A repulsive member **12a** is provided at a distal end of the second attachment member **12**. Similarly to the first attachment member **11**, the elongated hole **12b** (second angle adjustment section) and a pin hole **12c** are made in a hall-side side face of the second attachment member **12**. The second attachment member **12** is fixed to the car-side door panel **22** with the fitting **13** penetrating each of the elongated hole **12b** and the pin hole **12c**.

By adjusting the position for the fitting **13** to penetrate in each of the elongated holes **11b** and **12b**, which are arc-shaped elongated holes, it is possible to adjust the attachment angle of the first attachment member **11** relative to the first attachment member **11** and the attachment angle of the second attachment member **12** relative to the second attachment member **12**.

The first attachment member **11** and the second attachment member **12** are attached to hall-side side faces (back faces) of the car-side door panels **21** and **22**, so that a passenger in the car cannot usually touch the door hitting face **21a**. Further, when the hall-side door panels **31** and **32** are opened, the attachment angle of each of the first attachment member **11** and the second attachment member **12** can be adjusted from the hall.

However, although the configuration where the door-pinch detection device **10** is attached to the back faces of the car-side door panels **21** and **22** is described in the present application, the door-pinch detection device **10** may be attached to car-side side faces (front faces) of the car-side door panels **21** and **22**.

It should be noted that although the pin holes **11c** and **12c** are each a pin hole, the pin holes **11c** and **12c** may each be an elongated hole as the elongated holes **11b** and **12b**. With the pin holes **11c** and **12c** each being an elongated hole, it is possible to adjust the projection distance of the pressure sensor **11a** relative to the door hitting face **21a** and the retraction distance of the repulsive member **12a** relative to the door hitting face **22a**.

In the case shown in FIG. **4a** and FIG. **4b**, the projection distance refers to a distance from the door hitting face **21a** to a distal end of the pressure sensor **11a**. The retraction distance refers to a distance from the door hitting face **22a** to a distal end of the second attachment member **12**.

The pressure sensor **11a** is a string-shaped cylinder. A wire where a certain voltage or current is to flow is provided in the pressure sensor **11a**. When an alien object comes into contact with the pressure sensor **11a**, the shape of the pressure sensor **11a** deforms, causing a change in a resistance value of the current flowing in the pressure sensor **11a**. The alien object can thus be detected.

The pressure sensor **11a** is fixed to a distal end face of the first attachment member **11** with a bonding material, a tape, or the like.

The repulsive member **12a** is machined into a shape that covers the pressure sensor **11a** when the car-side door panels **21** and **22** are fully closed.

The repulsive member **12a** is provided with a recessed portion. When the car-side door panels **21** and **22** are fully closed, the pressure sensor **11a** is received in the recessed portion of the repulsive member **12a**. Thus, in the absence of an alien object, no pressure is applied to the pressure sensor **11a**.

In a case where a string-shaped alien object is pinched between the car-side door panels **21** and **22**, the repulsive member **12a** causes a tensile force to be generated in the string-shaped alien object. Thus, the tensile force generated

in the alien object causes a pressure to be applied to the pressure sensor **11a**, so that the alien object can be detected.

It should be noted that the first attachment member **11** and the second attachment member **12** are attached in a vertical direction over a range from lower ends of the car-side door panels **21** and **22** to a predetermined height (for example, 1.0 m to 1.5 m). This is because it is less necessary to reach a height higher than the level of the hand of a person, i.e., a height of 1.5 m or higher, with the assumption that a string-shaped alien object is usually a string for leashing a pet such as a dog.

Further, as shown in FIG. 4a and FIG. 4b, the pressure sensor **11a** is installed at a projected position in a door close direction with respect to the door hitting face **21a**, while the repulsive member **12a** is installed at a retracted position with respect to the door hitting face **22a**.

Installing at such positions makes, when a string-shaped alien object is pinched, a tensile force likely to be generated in the alien object, so that the accuracy of the pressure sensor **11a** in detecting an alien object can be improved.

With the pressure sensor **11a** projected with respect to the door hitting face **21a**, the accuracy of the pressure sensor **11a** in detecting an alien object can be further improved.

Inversely, the pressure sensor **11a** may be installed at a retracted position in the door close direction with respect to the door hitting face **21a**, while the repulsive member **12a** is installed at a projected direction with respect to the door hitting face **22a**.

Installing at such positions prevents the pressure sensor **11a** from projecting with respect to the door hitting face **21a**, so that a failure of the pressure sensor **11a** is less likely to be caused.

It should be noted that since the door hitting faces **21a** and **22a** are inclined in a V-shape in FIG. 4a and FIG. 4b, the projection distance of the pressure sensor **11a** relative to the door hitting face **21a** in FIG. 4b is smaller than that in FIG. 4a.

Assuming that the car-side door panel **21** is divided into at least upper side and lower side, at least the lower side, the pressure sensor **11a** projects with respect to the door hitting face **21a**. Such a configuration makes, when a string-shaped alien object is pinched, a tensile force likely to be generated in the alien object, so that the accuracy of the pressure sensor **11a** in detecting an alien object can be improved.

As described above, in Embodiment 1, the first attachment member **11** and the second attachment member **12** are provided with the angle adjustment sections, namely, the elongated holes **11b** and **12b**. This makes it possible to adjust the attachment angle of each of the first attachment member **11** and the second attachment member **12** even though the door hitting faces **21a** and **22a** are not in parallel but inclined, thus enabling an alien object pinched between the car-side door panels **21** and **22** to be detected with an improved accuracy.

It should be noted that although the configuration where the first attachment member **11** and the second attachment member **12** are both provided with the angle adjustment sections, namely, the elongated holes **11b** and **12b**, is described in Embodiment 1, it is sufficient if either one of the first attachment member **11** and the second attachment member **12** is provided with the angle adjustment section.

Further, in a case where the pressure sensor **11a** and the repulsive member **12a** are directly attached to the door hitting faces **21a** and **22a**, a door width is increased by an amount corresponding to the width of each of the first attachment member **11** and the second attachment member **12**, so that it is necessary to adjust the movable distance of

each of the car-side door panels **21** and **22** during the open and close motion or replace them with door panels each having a width smaller by an amount corresponding to the width of each of the first attachment member **11** and the second attachment member **12**.

However, in the configuration of the present application, the first attachment member **11** and the second attachment member **12** are fixed to not the distal end faces of the car-side door panels **21** and **22** but the side faces thereof, so that neither adjustment of the movable distance of each of the car-side door panels **21** and **22** nor replacement of the door panels is necessary.

Therefore, in newly attaching the door-pinch detection device of the present application to an elevator that has already been installed, the attachment work can be easily performed.

Embodiment 2

20 In Embodiment 1, description is made on the configuration where the first attachment member **11** and the second attachment member **12** are provided with the elongated holes **11b** and **12b** to allow the attachment angles of the first attachment member **11** and the second attachment member **12** to be adjusted.

In Embodiment 2, description will be made on a configuration where the angles of the first attachment member **11** and the second attachment member **12** relative to the door hitting faces **21a** and **22a** are automatically adjusted in accordance with the door close motion.

FIG. 5 is a perspective drawing of a door device including a door-pinch detection device of Embodiment 2. FIG. 6 is a C-C sectional drawing of FIG. 5.

In Embodiment 2, a first attachment member **51** and a second attachment member **52** are attached to the car-side door panels **21** and **22**, respectively.

The second attachment member **52** includes a fixation portion fixed with the fitting **13**, a repulsive member **52a**, and an intermediate portion provided between the fixation portion and the repulsive member **52a**.

An adjustment member **52c** (adjustment member) including an elastic blank material is inserted in the intermediate portion of the second attachment member **52**. The blank material of the adjustment member **52c** is, for example, a resin or the like.

An upper portion or a lower portion of the adjustment member **52c** is extended and retracted with respect to a door hitting face by a door hitting force to cause the second attachment member **52** to swingably move to enable the attachment angle to be adjusted.

The door close force of each of the car-side door panels **21** and **22** during door full close is set larger than the repulsive force of the pressure sensor **51a**.

The repulsive force of the repulsive member **52a** is set larger than the motion sensitivity of a pressure sensor to enable a string-shaped alien object to be detected by the pressure sensor. However, since an excessive repulsive force of the repulsive member **52a** is unlikely to allow the doors (the car-side door panels **21** and **22**) to be closed, a door pressing force for full close is set larger than the repulsive force of the repulsive member **52a**. The relationship of the repulsive force of the pressure sensor **51a**, the repulsive force of the repulsive member **52a**, and the door pressing force satisfies the following Expressions (1) and (2).

The repulsive force of the adjustment member
 $52c < \text{the door pressing force}$ (Expression 2)

A unit for the repulsive force of the pressure sensor **51a**, the repulsive force of the repulsive member **52a**, and the door pressing force is N.

In Expression W, the repulsive force of the pressure sensor **51a** is a value given by multiplying the motion sensitivity of the pressure sensor **51a** by the contact area (mm^2) of a pinched string or the diameter (mm) of the string. For example, in a case where the motion sensitivity of the pressure sensor **51a** is a value calculated by dividing the force (N) by the area (mm^2), a value given by multiplying the motion sensitivity (N/mm^2) by the contact area (mm^2) of the string is the repulsive force of the pressure sensor **51a**. Meanwhile, for example, in a case where the motion sensitivity of the pressure sensor **51a** is a value calculated by dividing the force (N) by a length (mm), a value given by multiplying the motion sensitivity (N/mm) by the contact length (mm) of the string is the repulsive force of the pressure sensor **51a**.

The repulsive force of the adjustment member **52c** is a value given by multiplying the elastic force (N/mm^2) of the adjustment member **52c** by the contact area (mm^2) of the string.

That is, the motion sensitivity (N/mm^2) of the pressure sensor **51a** is a value smaller than the elastic force (N/mm^2) of the adjustment member **52c**.

It should be noted that although the repulsive force of the pressure sensor **51a** and the repulsive force of the adjustment member **52c** are each a value dependent on the thickness of a string, the contact area and the contact distance of the string are the same between the pressure sensor **51a** and the adjustment member **52c**, so that a blank material that satisfies the conditions of Expression (1) may be selected by comparing the motion sensitivity of the pressure sensor **51a** and the elastic force of the adjustment member **52c** with each other. In other words, the adjustment member **52c** includes a blank material harder than that of the pressure sensor **51a**.

In Expression (2), the repulsive force of the adjustment member **52c** is a force (N) with which the entire adjustment member **52c** pushes back the door panels **21** and **22** when the doors are fully closed, and a door pressing force is a force (N) with which the door panels **21** and **22** are pushed when the doors are fully closed. Since door panels **21** and **22** cannot be closed if the blank material of the adjustment member **52c** is too hard, a blank material that satisfies the conditions of Expression (2) is selected or the door pressing force is increased.

As described above, in the configuration of Embodiment 2, the adjustment member **52c** is provided at the intermediate portion, which is not fixed with the fitting **13**, of the second attachment member **52**. This causes the repulsive member **52a** to automatically rotate by virtue of the pressing force of the car doors applied when the car-side door panels **21** and **22** are fully closed, enabling the repulsive member **52a** to be parallel with respect to the pressure sensor **51a**.

It should be noted that the adjustment member **52c** may include a spring or a leaf spring instead of a resin. Further, the fitting **13** inserted in the pin hole **52b** may include an elastic member with an elastic force.

It should be noted that although the configuration where the adjustment member **52c** is inserted in the intermediate portion of the second attachment member **52** is described, an adjustment member may be inserted in an intermediate portion of the first attachment member **51**. Alternatively, an

adjustment member may be inserted in the intermediate portion of each of the first attachment member **51** and the second attachment member **52**.

Embodiment 3

While the configuration where the first attachment member **11**, the second attachment member **12**, the first attachment member **51**, and the second attachment member **52** are each provided with an angle adjustment section is described in Embodiments 1 and 2, a configuration where the car-side door panels **21** and **22** are each provided with an angle adjustment section will be described in Embodiment 3 with reference to FIG. 7 and FIG. 8.

In Embodiment 3, respective third angle adjustment sections, namely, elongated holes **21b** and **22b**, are made in the car-side door panels **21** and **22**. The elongated holes **21b** and **22b** are each an arc-shaped elongated hole.

Respective pin holes **61b** and **62b** are made in the first attachment member **61** and the second attachment member **62**. The first attachment member **61** and the second attachment member **62** are fixed to the car-side door panels **21** and **22** with the fittings **13** inserted in the pin holes **61b** and **62b**.

With the holes made in the car-side door panels **21** and **22** each being an arc-shaped elongated hole, it is possible to adjust the attachment angles and the attachment positions of the first attachment member **61** and the second attachment member **62**. The attachment positions refer to the projection distance of the pressure sensor **61a** relative to the door hitting face **21a** and the retraction distance of the repulsive member **62a** relative to the door hitting face **22a**.

As described above, in the configuration of Embodiment 3, although neither the first attachment member **61** nor the second attachment member **62** has an elongated hole and neither the first attachment member **61** nor the second attachment member **62** includes an adjustment member, the angle adjustment sections, namely, the elongated holes **21b** and **22b**, provided in the car-side door panels **21** and **22** make it possible to adjust the attachment angles of the first attachment member **61** and the second attachment member **62**.

It should be noted that the pin holes **61b** and **62b** may each be an elongated hole as in Embodiment 1 instead of a pin hole. With the pin holes **61b** and **62b** each being an elongated hole, it is possible to more easily adjust the angles and the positions of the car-side door panels **21** and **22** in attaching them to the first attachment member **61** and the second attachment member **62**.

Further, in Embodiment 3, the fittings **13** each include a resin, a spring, or the like with an elastic force, so that the fittings **13** can be used as the adjustment members. In this case, even when the elongated holes **21b** and **22b** are each a pin hole, by virtue of the elastic forces of the adjustment members, the pressing forces of the car doors applied when the car-side door panels **21** and **22** are fully closed cause the pressure sensor **61a** and the repulsive member **62a** to automatically rotate, enabling them to be parallel with each other as in Embodiment 2.

Further, in a case of such a configuration, Expression (1) described above is satisfied.

FIG. 9 is a control flowchart for a door device including a door-pinch detection device. This control flowchart is applicable to the configurations of Embodiments 1 to 3.

In step 1 (S1), the door controller **40** judges, during the door close motion, whether or not the doors are within 30 mm from each other before being fully closed. If they are within 30 mm, the process proceeds to step 2.

11

In step 2 (S2), the door controller 40 judges whether or not the pressure sensor (11a, 51a, 61a) has detected an alien object. If the pressure sensor has detected an alien object, the process proceeds to step 3. If the pressure sensor has detected no alien object, the process proceeds to step 4.

In step 3 (S3), the door controller 40 transmits a running stop signal for the car to a control panel (not shown) in order for the car not to run. When receiving the running stop signal, the control panel performs a control to cause a traction machine (not shown) not to be driven.

In step 4 (S4), the door controller 40 judges whether or not a predetermined time (for example, 3 seconds) has elapsed since the start of the running of the car. If the predetermined time has elapsed, the process proceeds to S1. If the predetermined time has not elapsed, the process returns to S2. It should be noted that the predetermined time may be set at the time of shipment from the factory or may be changed by a maintainer after the elevator is installed.

By providing S4, even after the running of the car is started, detection performed by the pressure sensor is to continue until the predetermined time elapses. The running of the car can be stopped even if the pressure sensor detects an alien object immediately after the running of the car is started, which enabling the safety of the elevator to be improved.

Although Embodiments 1 to 3 described above each relate to a double-doored configuration, a similar effect can be obtained in a case of a single-swinging door by attaching one of a pressure sensor and a repulsive member to a door-hitting-side frame.

The invention claimed is:

1. A door-pinch detection device, comprising:
 a first attachment section and a second attachment section attached to at least either side face of a front face or a back face of a door panel of an elevator, the first attachment section including a pressure sensor, the second attachment section including a repulsive member installed in a manner for the pressure sensor to be housed therein; and
 at least either one of a first angle adjustment section provided in the first attachment section to adjust an attachment angle of the pressure sensor with respect to the door panel for installation or a second angle adjustment section provided in the second attachment section

12

to adjust an attachment angle of the repulsive member with respect to the door panel for installation, wherein the pressure sensor is configured to detect an alien object.

2. The door-pinch detection device according to claim 1, wherein

the first angle adjustment section includes an elongated hole made in the first attachment section,
 the second angle adjustment section includes an elongated hole made in the second attachment section, and
 the first attachment section or the second attachment section is fixed to the door panel with the attachment angle adjusted by adjusting a position for a fitting to penetrate the elongated hole, the fitting penetrating the elongated hole and being fixed at a hole made in the front face or the back face of the door panel.

3. The door-pinch detection device according to claim 1, wherein

the first angle adjustment section includes an adjustment member with an elastic force provided in the first attachment section,
 the second angle adjustment section includes an adjustment member with an elastic force provided in the second attachment section, and
 each of the adjustment members causes the pressure sensor or the repulsive member to swingably move.

4. The door-pinch detection device according to claim 3, wherein the adjustment member is a resin.

5. The door-pinch detection device according to claim 3, wherein the adjustment member is a spring.

6. The door-pinch detection device according to claim 3, wherein a repulsive force of the adjustment member is larger than a motion sensitivity of the pressure sensor and smaller than a pressing force applied to a door hitting face of the door panel when doors of the elevator are closed.

7. The door-pinch detection device according to claim 1, wherein the pressure sensor is installed to project with respect to a door hitting face of the door panel.

8. The door-pinch detection device according to claim 1, wherein the pressure sensor is installed to retract with respect to a door hitting face of the door panel.

9. An elevator door device, comprising:
 a door panel of an elevator;
 a door-pinch detection device including a first attachment section and a second attachment section installed on at least either one of a front face or a back face of the door panel, the first attachment section including a pressure sensor, the second attachment section including a repulsive member installed in a manner for the pressure sensor to be housed therein when doors of the elevator are closed; and

an angle adjustment section provided in the door panel to adjust an attachment angle of at least either one of the first attachment section or the second attachment section for installation, where the pressure sensor is configured to detect an alien object.

10. The elevator door device according to claim 9, wherein

the third angle adjustment section includes an elongated hole made in at least either one of the front face or the back face of the door panel, and
 at least either one of the first attachment section or the second attachment section has a hole penetrating therethrough and is fixed to the elongated hole at an angle relative to a door hitting face of the door panel with a fitting penetrating the hole.

11. The elevator door device according to claim 10, wherein

the third angle adjustment section includes an adjustment member with an elastic force, and the adjustment member causes the pressure sensor or the repulsive member to swingably move.

12. The elevator door device according to claim 11, 5 wherein the adjustment member is a resin.

13. The elevator door device according to claim 11, wherein the adjustment member is a spring.

14. The elevator door device according to claim 11, wherein a repulsive force of the adjustment member is larger 10 than a motion sensitivity of the pressure sensor and smaller than a pressing force applied to a door hitting face of the door panel when the doors are closed.

15. The elevator door device according to claim 9, wherein the pressure sensor is installed to project with 15 respect to a door hitting face of the door panel.

16. The elevator door device according to claim 9, wherein the pressure sensor is installed to retract with respect to a door hitting face of the door panel.
